FIG. 4.

FIG. 5.

INVENTOR

William E. Ferguson

UNITED STATES PATENT OFFICE.

WILLIAM E. FERGUSON, OF BUFFALO, NEW YORK.

AUTOMATIC LID-RELEASING DEVICE FOR TALKING-MACHINE AND LIKE CABINETS.

1,289,718.

Specification of Letters Patent. Patented Dec. 31, 1918.

Application filed January 10, 1917. Serial No. 141,542.

To all whom it may concern:

Be it known that I, WILLIAM E. FERGUSON, a citizen of the United States, and a resident of Buffalo, in the county of Erie and State 5 of New York, have invented a new and Improved Automatic Lid-Releasing Device for Talking-Machine and like Cabinets, of which the following is a full, clear, and exact description.

10 My invention relates to cabinets which have a hinged lid or top with a lid-support arm pivoted thereto and a catch therefor on the body of the cabinet, and has for its object to provide means for automatically disengaging the lid-support from the catch when the lid is seized and operated to be closed, so that in lowering the lid it is not necessary to manually operate the lid-support.

15 Another object of my invention is to provide a device of this character in the form of an attachment capable of being readily applied to talking machines and like cabinets in use.

20 With these objects in view, the invention consists generally stated, of an arm member adapted to force the lid-support away from the catch, and a second member adapted to engage and latch with the arm member, and 25 a spring acting on the said members to actuate them.

25 The inventive idea involved is capable of receiving a variety of mechanical expressions, one of which, for the purpose of illustrating the invention, is shown in the accompanying drawings. Such drawings are not to be taken as defining the limits of the invention, reference being had to the claims for that purpose.

30 In said drawings, Figure 1 is a vertical section through the upper part of the casing of a cabinet with the lid or top thereon, equipped with my invention:

35 Fig. 2 is a fragmentary section on an enlarged scale showing the position of the automatic release when the lid-support is moving into engagement with the catch provided for the purpose;

40 Fig. 3 is a view similar to Fig. 2 but showing the parts in position with the lid-support completely engaging the catch member;

45 Fig. 4 is a similar view showing the positions of the lid-support and the automatic release when the lid has been lifted to the maximum extent preparatory to lowering same, and showing said support swung

away from the catch by the action of the device;

50 Fig. 5 is a similar view but showing the parts in position when the lid is completely closed, and also showing the means by which the device is automatically reset by the lid-support as the lid is closed.

55 In all the views of the drawing, like parts are designated by the same reference characters.

60 Referring more particularly to the example of my invention illustrated in Figs. 1 to 5, reference character 1 indicates the lid or top of the cabinet 2 of a talking machine; 70 3, the usual partition on which the turntable, etc., are mounted; 4, the usual lid-support pivoted at its upper end to the lid 1 by a bracket 7, and having a slot 5 in its lower end to engage with the usual catch 8, 75 when the lid is fully opened; 9, a slot in partition 3 to accommodate lid-support 4. A slotted guide plate 10, through which lid-support 4 extends, is secured by screws to partition 3, over slot 9, serves to guide lid-support and adds a finish. To limit the upward travel of support 4, a stop pin 11 is located in same. All the parts referred to are known.

80 I provide an arm 12 pivotally mounted for 85 swinging movement about a fixed axis by a pivot bearing 15, to a plate 16, the arm 12 having a projection 13 that is formed integral therewith, an arm 14 is secured to and preferably formed integral with arm 12. 90 The parts 12, 13 and 14 may be conveniently formed, as by stamping, from a single piece of sheet metal.

95 An arm 17 is also pivotally mounted to the plate 16, by a pivot bearing 21, and having shoulders or abutments 18 and 19 formed therein for engaging and latching with the arm 14, an arm 20 is attached to and preferably formed integral with arm 17, the arm 20 terminates in close proximity to the usual 100 catch 8 which in this case is a short pin or stud securely riveted to the plate 16, this arm is so positioned that the nose 6 on lid-support 4 will depress the arm 20 when the lid or top is retained open by lid-support 4 105 resting on catch 8. The parts 17 and 20 may be conveniently formed, as by stamping, from a single piece of sheet metal.

110 A helical spring 22 is attached at one end by a pin or stud 23 to arm 14, the other end is attached to arm 17 by a pin or stud 24. This spring is under tension and forces arm

12 to swing outward against lid-support 4 when arm 14 is released by abutment or shoulder 18 on arm 17 when the latter is swung outward by arm 20 when the latter is depressed by nose 6 on lid-support 4. This spring also forces arm 17 to return to its latching position with arm 14, and carrying arm 20 to its set position.

A flat plate 16, which can be made by stamping from sheet metal, carries the arms 10 12, 14, 17 and 20, and the catch 8. I show this plate attached to the under side of slotted guide plate 10, this can be done in any suitable manner, such as butt-welding. By 15 this construction the entire device is self-contained and held in position on partition 3 by screws through slotted plate 10, as shown. Plate 16 is made of such a size and shape that will readily go through slot 9 20 in partition 3. If desired plate 16 can be separate from slotted guide plate 10, and attached directly to the side of the cabinet by screws or any other means (not shown).

The arm 12 is so positioned and has sufficient motion to swing lid-support 4 entirely 25 clear of catch 8, leaving the lid 1 free to be lowered. The length of arms 17 and 20, is such, that the motion imparted to arm 20 by nose 6 on lid-support 4, will be sufficient to swing arm 17 enough to freely clear 30 arm 14 from contact with abutment or shoulder 18. The shoulder or abutment 19 formed in arm 17 serves as a stop against which arm 14 strikes, limiting the motion 35 of arm 12.

In operation when lid 1 is raised, support 4 is in position to engage catch 8, as shown in Fig. 2, as lid 1 is slightly lowered as usual to cause support 4 to completely hook-over 40 catch 8, nose 6 on said support comes into contact with arm 20 and depresses same, thereby causing arm 17 to swing away from arm 14, releasing the latter from abutment 18, as shown in Fig. 3. As lid 1 is slightly raised as usual to allow nose 6 to swing clear 45 of catch 8, arm 12 under the influence of spring 22, swings on its pivot bearing 15, and forces support 4 away from catch 8, as shown in Fig. 4. The outward swing of 50 arm 12 is stopped by arm 14 striking against abutment 19 on arm 17. As the lid is being lowered carrying with it lid-support 4 the lower end of the latter has a swinging motion toward arm 12 and comes into contact 55 with projection 13 on arm 12, forcing arms 12 and 14 back to their set or cocked position, where they are held by abutment 18 on arm 17 latching over arm 14 under the influence of spring 22 connecting said arms. 60 Fig. 2 also shows these members in their set or cocked position. When lid 1 is completely closed the edge of lid-support 4 bears against the end of the slot in slotted guide plate 10, thereby causing 65 said support 4 to positively reset the de-

vice to its cocked position, as shown in Fig. 5.

It is to be understood that many changes may be made in the shape and arrangement of the parts of the specific embodiments shown and described herein without any departure from the spirit or scope of the invention.

Having now described my invention, what I claim as new and desire to protect by Letters Patent of the United States is as follows:

1. Top-releasing device, which comprises in combination with a top-prop and a catch therefor, a movable member to engage said top-prop, and a second movable member to engage said first movable member, said second movable member being operated by said top-prop.

2. The combination with a swinging lid-support and a relatively fixed catch therefor; of means to resiliently engage said support and adapted to deflect the same from the supporting position in engagement with the catch, said means including a rockable element to contact with the support; and a second rockable element controlling the movements of the first means, said second rockable element being movable by the said support.

3. An automatic lid-releasing device, which comprises in combination with a lid-support and a catch therefor, means for automatically forcing said support from contact with said catch; comprising a member adapted to deflect said support away from said catch, and a second member adapted to engage with and retain and release said first member.

4. An automatic lid-releasing device, which comprises in combination with a lid-support and a catch therefor, means for automatically forcing said support from contact with said catch; comprising a member adapted to deflect said support away from said catch, a second member latching with said first member adapted to retain and release the latter, said second member being operated by said support, said first member being released by said second member when said second member is operated by said support, and a spring acting on said members.

5. An automatic lid-releasing device, which comprises in combination with a lid-support and a catch therefor, means for forcing said support from contact with said catch; comprising a member adapted to deflect said support away from said catch, a second member latching with said first member, said second member adapted to latch 125 with and release said first member, said second member being operated by said support, said first member being released by said second member when said second member is operated by said support, a spring acting on 130

- said members, means for resetting said members to their set position, comprising a projection on said first member, said support bearing against said projection as said support travels downward forcing said first member back to its set position where it is latched in place by said second member returning to its set position under the action of said spring.
5. In a cabinet, the combination of a body, a lid hinged thereto, a lid-prop and a catch therefor attached to said body, a movable member adapted to engage said lid-prop, and a second movable member adapted to engage said first movable member, said second movable member being operated by the lid-prop.
10. 6. In a cabinet, the combination of a body, a lid hinged thereto at one edge, a lid-support connected to the lid and engaging with a catch on the body, and automatic means 35 for moving said lid-support out of engagement with said catch, comprising a spring-pressed arm pivoted to the body, means for controlling the action of said arm, comprising a member that releasably latches with 40 said arm, said member being actuated by said lid-support, and means for automatically resetting said arm and said member by said lid-support as the lid is closed.
15. 7. In a cabinet, the combination of a body, a lid hinged thereto at one edge, a lid supporting device connected to the lid and having engagement with a catch on the body, and automatic means for moving said supporting device out of engagement with said

catch, comprising an arm pivoted to said body and bearing against said supporting 25 device when the latter is in engagement with said catch, a spring acting on said arm, and means for controlling the action of this arm comprising a member that releasably engages with said arm, said member being operated by said lid supporting device.

8. In a cabinet, the combination of a body, a lid hinged thereto at one edge, a lid-support connected to the lid and engaging with a catch on the body, and automatic means 35 for moving said lid-support out of engagement with said catch, comprising a spring-pressed arm pivoted to the body, means for controlling the action of said arm, comprising a member that releasably latches with 40 said arm, said member being actuated by said lid-support, and means for automatically resetting said arm and said member by said lid-support as the lid is closed.

WILLIAM E. FERGUSON.
